FIG.4

FIG. 5

FIG. 6

FIG. 1 is a front elevational view of the postal scale or the like embodying the new design;

FIG. 2 is a side elevational view of the postal scale or the like of FIG. 1, the opposite side of which is identical except for the omission of the circular knob;

FIG. 3 is a top plan view of the postal scale or the like of FIG. 1;

FIG. 4 is a rear elevational view of the postal scale or the like of FIG. 1;

FIG. 5 is a front perspective view of the postal scale or the like of FIG. 1, taken from the front right of FIG. 1 and somewhat from above looking down; and

FIG. 6 is a rear perspective view of the postal scale or the like of FIG. 1, taken substantially diametrically opposite to the view of FIG. 5.

The essential features of the design reside in the full line portions thereof.

I claim:

The ornamental design for a postal scale or the like, as shown and described.
